UNITED STATES PATENT OFFICE.

OLIVER MITCHELL, OF BROOKLINE, MASSACHUSETTS.

PACKAGE FOR BRAID OR THE LIKE.

Application filed March 30, 1921. Serial No. 456,892.

To all whom it may concern:

Be it known that I, OLIVER MITCHELL, a citizen of the United States, residing at Brookline, in the county of Norfolk and State of Massachusetts, have invented certain new and useful Improvements in Packages for Braid or the like, of which the following is a specification.

My invention relates to an improved device for packaging braid, shoe laces, yarns, or the like, in relatively small quantities, in such fashion that the material may be easily arranged in the package, thoroughly protected and so secured that the contents of the package cannot for practical purposes, be removed without destroying the package in which the material is secured.

To this end I provide two covers of card-board or the like, to one or both of which is attached a projecting spindle or material receiving portion.

In the drawings, I have shown in Figure 1, an outline of a single spindle blank and in Figure 2, an outline of a double spindle blank. In Figure 3, the package of Figure 1, complete, is shown in edge view. In Figure 4, the package of Figure 2, complete, is shown in edge view.

In the drawings, A and A' are cover portions, and B and B' spindle portions, of the package, the package material being creased (as shown in dotted lines) to form folding or hinged parts, as at c. The spindle parts preferably carry at their ends heads, a. At the end of the cover portion, are sealing tabs, b. Apertures a', are preferably formed in heads a.

In loading the package, the tabs b are first bent over against the cover part, as shown in Fig. 1. The cover parts are then secured between two clamping plates, rotatably mounted, leaving the spindle part of the package projecting. One end of the material is threaded through an aperture a' and the clamping plates rotated to wind on the material, the other end of the material being threaded, at the end of the winding operation, through the other aperture a'. The spindle with its load is now bent to lie alongside the cover to which it is connected, and the other cover (with its loaded spindle, if it is a two spindle package) is then bent to lie alongside the spindle and the other

cover, the spindle or spindles lying between the covers. The sealing tabs, b, which are slotted as at b' are then interlocked with the slots b² in the cover (see Figs. 3 and 4) and if desired, cemented or eyeleted in place.

It will now be apparent that the ends of the material are threaded securely through the material of the package and turned into the package, and that the material itself is coiled about a spindle in many loops, so that the ends of the material are inaccessible and the loops also, within a sealed package. The material therefore cannot be removed save by breaking the seal and opening the covers.

It will also be obvious that the covers, owing to their relative width will extend beyond the material, preventing any contact of the material carried with outer things, while at the same time permitting free observation for color, size, etc.

I claim:

1. A package for braid or the like, made up of a pair of relatively wide cover parts, connected at their ends and carrying a relatively narrow spindle, or load receiving extension at the free end of the cover, adapted to be folded in between the covers. 75

2. A package for braid or the like, made up of a pair of relatively wide cover parts, connected at their ends and carrying a relatively narrow spindle or load receiving extension at the free end of the cover, adapted to be folded in between the covers, the spindle being provided at its free end with an apertured head to receive the end of the 85 braid.

3. A package of braid or the like, made up of a pair of relatively wide cover parts, connected at their ends and carrying a relatively narrow spindle, or load receiving extension at the free end of the cover, adapted to be folded in between the covers, the spindle being provided at its free end with an apertured head to receive the end of the 95 braid, the braid being wound in helical coils 100 about the spindle and its free end threaded through the apertured head.

Signed at Boston, Massachusetts, this twenty-eighth day of March, 1921.

OLIVER MITCHELL.
